(57) CLAIM

The ornamental design for a television receiver, as shown and described.

DESCRIPTION

FIG. 1 is a front elevational view of a television receiver showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view of the top, front and right side thereof;

FIG. 8 is a front elevational view with the side pieces moved closer to the center piece; and,

FIG. 9 is a perspective view similar to FIG. 7 with the side pieces tilted.
